US00D970722S

(12) **United States Design Patent** (10) **Patent No.:** **US D970,722 S**
(45) **Date of Patent:** **** Nov. 22, 2022**

(54) **MEDICAL INJECTOR**

(71) Applicant: **Guotao Zeng**, Jieyang (CN)

(72) Inventor: **Guotao Zeng**, Jieyang (CN)

(**) Term: **15 Years**

(21) Appl. No.: **29/775,802**

(22) Filed: **Mar. 25, 2021**

(30) **Foreign Application Priority Data**

Dec. 7, 2020 (CN) 202030751135.8

(51) **LOC (13) Cl.** **24-02**

(52) **U.S. Cl.**

USPC **D24/114**

(58) **Field of Classification Search**

(57) **CLAIM**

The ornamental design for a medical injector, as shown and described.

DESCRIPTION

FIG. 1 is a front perspective view of a medical injector of the present disclosure according to a first embodiment;

FIG. 2 is a rear perspective view thereof;

FIG. 3 is a front elevational view thereof;

FIG. 4 is a rear elevational view thereof;

FIG. 5 is a left-side elevational view thereof;

FIG. 6 is a right-side elevational view thereof;

FIG. 7 is a top plan view thereof; and

FIG. 8 is a bottom plan view thereof.

FIG. 9 is a front perspective view of a medical injector of the present disclosure according to a second embodiment;

FIG. 10 is a rear perspective view thereof;

FIG. 11 is a front elevational view thereof;

FIG. 12 is a rear elevational view thereof;

FIG. 13 is a left-side elevational view thereof;

FIG. 14 is a right-side elevational view thereof;

FIG. 15 is a top plan view thereof; and,

FIG. 16 is a bottom plan view thereof.

1 Claim, 16 Drawing Sheets
